(57) **CLAIM**

The ornamental design for a cooking burner, as shown and described.

DESCRIPTION

FIG. 1 is a front perspective view of a cooking burner according to the design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a back elevation view thereof.

The portions of the article shown in broken line form no part of the claimed design.

1 Claim, 5 Drawing Sheets
